JOHN BLAKE TARR, OF FAIRHAVEN, MASSACHUSETTS.

Letters Patent No. 94,253, dated August 31, 1869; antedated August 25, 1869.

IMPROVEMENT IN PRESS FOR CASTING METAL.

The Schedule referred to in these Letters Patent and making part of the same.

To all whom it may concern:

Be it known that I, JOHN BLAKE TARR, of Fairhaven, in the county of Bristol, and State of Massachusetts, have invented a new and improved Machine for Producing Compressed Metal Castings; and I do hereby declare that the following is a full, clear, and exact description thereof, reference being had to the accompanying drawings, making a part of this specification, in which—

Figure 1 is a front elevation of a machine adapted for producing compressed metal ingots, showing the mould in proper position for receiving the follower, which latter is represented in the act of descending to the upper end of said mould.

Figure 2 is a transverse section through fig. 1, in the vertical plane indicated by red line x x , showing the follower depressed, in the act of condensing the metal in the mould.

Figure 3 is a similar view of the same parts shown in fig. 2, representing the follower and its guide-rods and screw inclined so as to expose the top of the mould, for allowing metal to be poured into it.

Figure 4 is a bottom view of the head of the machine, as seen by a section taken through fig. 1, in the horizontal plane indicated by red line y y .

Similar letters of reference indicate corresponding parts in the several figures.

This invention relates to a new and useful improvement on machinery which is adapted for producing compressed metal castings, in which a follower or pressing-head is employed, and so arranged over the mould in which the castings are produced, that when said mould is supplied with melted metal, this metal can be subjected to considerable pressure, and thereby condensed, so as to render it more solid than it otherwise would be.

The advantages attending metal thus compressed and condensed, are fully set forth in the schedule annexed to my Letters Patent, numbered, respectively, 57,644, 67,000, 79,611, and 83,222.

The object of this invention is to so arrange and support the follower or pressing-head over a mould, that this follower or head can be moved to one side of the mould, so as to expose the upper end of the latter for conveniently pouring the melted metal into it, at the same time to provide means which will allow the follower or head to be quickly returned to a proper position over the mould, for applying pressure for condensing the melted metal before it begins to set or become hard, as will be hereinafter explained.

To enable others skilled in the art to understand my invention, I will describe its construction and operation.

In the operation of producing compressed metal castings by subjecting the metal, while in a fluid state in the moulds, to considerable pressure, I have found, by

experiment, that the best results are obtained if the pressure is applied to the metal in the moulds before it becomes so hard or set that the gases are entrapped and their expulsion rendered imperfect.

To effect this object, and at the same time to provide for exposing the upper end of a mould to allow metal to be poured into it conveniently, the follower or pressing-head A is applied to a hinged nut, H, which will allow the follower to be swung or tilted, as shown in fig. 3, and quickly brought back to the vertical position shown in figs. 1 and 2, thereby rendering it unnecessary to raise the follower higher than will allow it to clear the top of the mould when tilted, as shown in fig. 3.

In the accompanying drawings—

C represents the bed of the press-frame; and

D are strong upright pillars, which sustain the head-plate C, and by means of which this plate is restrained from rising against considerable upright pressure.

E represents a rectangular mould, which is adapted for making ingots, and which is constructed of two vertical halves or sections, with a wide base, a, which sections are lined inside with any suitable refractory substance, indicated in the drawings by letter b.

The sections of this mould E are clamped together by means of bands c c and wedges d d, and the mould is centred and confined in its proper place beneath its pressing devices by means of adjustable stops e e and turning-hooks f f. These stops and hooks are made adjustable for accommodating them to moulds of different sizes.

The bottom and vertical sides of the mould are closed, and the top is left open to receive the end of the follower A, as shown clearly in the drawings.

The follower A is constructed with flanges g g extending out laterally from its upper end, by which screws h h can be used for confining it to a horizontal head-piece F. This will allow of the ready removal of one follower, and the substitution of another of a different size or shape, adapted to the ingot which it is desired to produce. The follower A should be slightly smaller, horizontally, than the receptacle in the mould, for the purpose of allowing a free escape of gases during compression.

The head-piece F is applied, by a swivel-connection, to the lower end of a screw, G, which is tapped through a nut, H, and which carries on its upper end lever-arms I I, that can be removed at pleasure, and longer or shorter ones applied in their stead.

This head F has also applied to it two rods J J, which pass freely through the nut H, on opposite sides of screw G, and serve as guides for the head F and screw G, and prevent this head from turning around with the screw, in the act of raising or depressing the follower.

The nut H is pivoted by trunnions i i to boxes j j,

which are secured firmly to the bottom of the head C' of the press-frame; and this nut is so arranged that when it is held in a horizontal position, shown in figs. 1, 2, and 4, by means of a sliding-catch k, the axis of the screw G will coincide with the vertical centre of the mould E and follower A.

The catch k has a hand-lever, m, pivoted to it, by which it can be readily moved for fastening or releasing the nut, and this lever is connected by a vibrating link, m', to the bottom of the head C' of the press-frame, as shown in fig. 4.

When mould E is adjusted in proper position upon the bed C of the press-frame, and confined in place, and everything is ready for pouring melted metal into the mould, the operator, with his hand upon the lever m, withdraws catch k, and releases one edge of the nut H, thus allowing the latter, with its follower A, screw G, and guide-rods J J, to assume the inclined position shown in fig. 3. Sufficient space will thereby be left, above the mould E, for conveniently pouring metal into it.

When the mould is filled, the operator instantly draws back the follower and its attachments, locks the nut in place, as shown in figs. 1, 2, and 4, and causes the follower to descend by turning the screw G.

By thus providing for inclining the follower and its attachments from a vertical position over the mould, when it is desired to fill the mould, it will be seen that it will only be necessary to raise the follower a short distance to allow it to swing clear of the mould, whereas without such provision it would be necessary to raise the follower so high, to obtain the required space for pouring, that after the metal was poured into the mould it would become cool and set before the follower could be brought down again by the slow screw G, and made to press upon it.

It will be seen, by reference to fig. 3, that when the follower is inclined from a vertical position, that the screw G rests against one side of the opening through head C', through which this screw and its guide-rods pass.

In order to prevent a ready destruction of the mould, and to admit of a mould being used for a number of

castings, I line or cover its inner surface with a refractory compound, represented by letter b. I also coat the bottom surface of the follower with the same compound.

In the section of a protecting coating for the mould and follower, it is important to employ a compound which will adhere firmly to the surfaces to which it is applied, and which will not expand or contract very much; also to employ a substance which will not melt and form a slag, when subjected to the intense heat of the melted metal.

The following method of preparing the mould is found to be best adapted to the end in view:

A core is introduced into the mould, of such size as will leave a space of about one-half or three-quarters of an inch between it and the inner wall of the mould, into which space sharp moulding-sand is rammed very hard. This sand is prepared by mixing with it rye-meal and molasses, say about fifteen parts of sand to one part of a mixture of rye-meal and molasses.

The mould is then put into an oven, and baked for about twelve hours, after which it is taken out and its lining coated, while hot, with a solution composed of about one part of plumbago to three parts of fire-clay, made thin by adding beer to them. After coating the mould repeatedly, and drying each coating, the surfaces are smoothed.

The last coating given to the mould should be very thick, so that it will partially fill up the pores in the sand, and leave hard and smoothed surfaces.

Having described my invention,

What I claim as new, and desire to secure by Letters Patent, is:

1. The follower A, attached to a screw, G, which works through a pivoted nut, H, in combination with a mould, substantially as and for the purpose described.

2. The combination in a press of a follower A, and its screw G, and guide-rods J J, with a laterally adjustable nut H, substantially as described.

JOHN BLAKE TARR.
